PANTS HANGER

Mayo E. Leonard, Toledo, Ohio

Application May 19, 1949, Serial No. 94,169

2 Claims. (Cl. 223—95)

1

My invention relates to pants hangers of the type adapted for gripping action in the legs of the pants to suspend the same, and as exemplified in my U. S. Letters Patent No. 2,017,761 dated October 15, 1935, over which this invention is designed as an improvement.

The primary object of this invention is to simplify the construction of such hangers, and provide for easier and quicker assembly of parts, together with greater gripping action, all to the end of reducing the cost of manufacture and attaining greater efficiency in operation.

Another object is to provide for retaining the assembled parts of such hangers in proper relation by improved means obviating special screw studs, rivets, and the like, which increase the cost of manufacture of said hangers.

Still another object is to provide in such hangers for rotating the hanger bar on the suspension hook into different positions in which the bar is yieldingly locked, whereby to facilitate hanging pants in closets, or on display, in different positions as may be found desirable.

Other and subordinate objects within the purview of my invention, together with the precise nature of my improvements, will be readily understood when the succeeding description and claims are read with reference to the drawings accompanying and forming part of this specification.

In said drawings:

Figure 1 is a view in side elevation of my improved pants hanger in a preferred embodiment thereof with a pair of pants, shown fragmentarily, suspended therefrom;

Figure 2 is a view in end elevation;

Figure 3 is a fragmentary view in vertical longitudinal section drawn to a larger scale;

Figure 4 is a fragmentary view in horizontal section taken on the line 4—4 of Figure 3;

Figure 5 is a view in vertical transverse section taken on the line 5—5 of Figure 1 and drawn to a larger scale;

Figure 6 is a similar view taken on the line 6—6 of Figure 1 and drawn to a still larger scale;

Figure 7 is a view in transverse section illustrating the hanger bar rotated into a position at a right angle to the plane of the suspension hook;

Figure 8 is a view in horizontal section taken on the line 8—8 of Figure 7 and drawn to a larger scale;

Figure 9 is an exploded view in perspective of parts of the pants hanger;

Figure 10 is a fragmentary view in perspective of the stem of the hanger hook; and

Figure 11 is a view in perspective of one of the guide pins.

Referring to the drawings by numerals, my improved pants hanger comprises as its basic parts a tubular hanger bar 1, a central suspension hook 2 for said bar, and a pair of grips 3 for insertion in the legs of pants designated 4.

The hanger bar 1 may be of any suitable diameter and length rendering the same suitable for use in the manner presently seen, and is preferably formed of light strong metal, such as stainless steel, or aluminum, but, may be formed of plastic if desired.

The suspension hook 2 is formed of a suitable gauge rod material, preferably metal, with a shank 5 on which the hanger bar 1 is secured at its transverse center by rotatably inserting said shank 5 through said bar 1, and upsetting the terminal end of the shank 5, as at 6. Inside the hanger bar 1, the shank 5 is square, in cross-section, to provide a pair of opposite flat sides 7 parallel to the plane of the hanger hook 2, and another pair of opposite flat sides 8 at right angles to the plane of said hook, all for a purpose presently explained.

The grips 3, which may be formed of any suitable light strong metal, or plastic, comprise a pair of longitudinally split cylindrical sleeves 9 fitting around said bar 1 on opposite sides of the hanger hook 2 for sliding along said bar and having formed integrally therewith outer end extensions 10 of bifurcated form in cross section straddling said bar 1 and each including a pair of laterally spaced gripping plates 11 with notched outer side edges 12. The sleeves 9 are formed at the inner ends thereof with a pair of upstanding manipulative horns 13 curving toward the outer ends of said grips 3 and for grasping between the thumb and finger of one hand and pressing toward each other to slide said grips 3 toward each other along the hanger bar 1, as will be understood. The pairs of gripping plates 11 are designed to be inserted in the legs 14 of the pants 4, as shown in Figures 1, 2 and 5, in the creases of the pants, and the grips 3 to be forced outwardly and guided along the hanger bar 1 to cause the notched edges 12 of said plates 11 to grip said legs 14 and thereby suspend the pants with the bottom of the legs 14 stretched, all by means now to be described.

A pair of flat guide pins 15 of substantially the same length as the outside diameter of the sleeves 9 are slidably inserted through side slots 16 in the sleeves 9 and through pairs of diametrically opposite, longitudinal guide slots 17 in the sides 55 of the hanger bar 1 to prevent said grips 3 from

turning around said bar 1. The pins 15 are provided with notched inner edges, as at 18. A pair of expanding coil springs 19 are interposed in the hanger bar 1 between the pins 15 and the shank 5 of the suspension hook 2. The coil springs 18 at the outer ends thereof fit in the notches 18 of the guide pins 15, and are thereby recessed into said pins, for a particular purpose presently explained.

As will be apparent, the notched guide pins 15 and the shank 5 of the suspension hook 2 retain the coil springs 19 in place in the hanger bar 1 while the guide pins 15 are retained in place by the ends of the coil springs 19 fitting in the notches 18 of said pins. The inner ends of the coil springs 19 seat flat against the pair of flat sides 7 of the shank 2 when the hanger bar 1 is rotated on said shank into a common plane with the hanger hook 2, and said inner ends of the coil springs 19 similarly seat against the pair of flat sides 8 of the shank 5 when said bar is rotated into a position at a right angle to the plane of the suspension hook 2, whereby said bar 1 is yieldingly locked in either position described relative to said suspension hook.

In using and operating the improved pants hanger, the horns 13 may be grasped between the thumb and forefinger of one hand and pressed together to slide the grips 3 toward each other along the hanger bar 1, in opposition to the coil springs 19, to position said grips for insertion in the legs 14 of the pants 4 held in the other hand. Then, upon relieving pressure on said horns 13, the grips 3 will be forced by the coil springs 19 outwardly along the hanger bar 1 to force the gripping plates 11 into gripping position in the legs 14, in the manner already described. The hanger may be suspended by the suspension hook 2 from the usual horizontal pole, shown in dotted lines at 20, or any other fixed support, with the hanger bar 1 rotated on the shank 5 and yieldingly locked in rotated position to arrange the pants 4 in either of two relatively right angled positions, the advantage of which will be manifest.

The foregoing will, it is believed, suffice to impart a clear understanding of my invention, without further explanation.

Manifestly, the invention, as described, is susceptible of modification without departing from the inventive concept, and right is herein reserved to such modifications as fall within the scope of the appended claims.

Having described the invention, what is claimed as new is:

1. In a pants hanger, a tubular hanger bar provided adjacent each end with a pair of diametrically opposite longitudinally extending slots therein, a hanger hook having a shank extending centrally through said bar and about which said bar is rotatable into different positions, a pair of pants grips carried by said bar upon opposite sides of said shank and including a pair of sleeves slidable outwardly along said bar to correspondingly slide said grips into pants gripping position, said sleeves having diametrically opposite slots therein, a pair of pins extending diametrically through said bar with ends slidable in the pairs of slots in the bar and fitting in the pairs of slots in the sleeves to guide said sleeves during sliding thereof and correspondingly guide said grips, a pair of coil springs 10 in said bar having inner ends bearing against opposite sides of said shank and outer ends bearing against said pins to slide the pins in the slots in the bar and thereby slide said sleeves, said pins being notched to seat the outer ends 15 of the springs therein to prevent the pins from working out of said slots, and means on said shank coating with the inner ends of said springs to yieldingly lock said bar in different positions into which the same is rotated.
2. A pants hanger according to claim 1, said means including flattened sides on said shank against which the inner ends of the springs seat.

MAYO E. LEONARD.
